UNITED STATES PATENT OFFICE.

WILLIAM H. ROGERS, OF PLAINFIELD, NEW JERSEY.

DESIGN FOR A HANDLE FOR SPOONS, FORKS, OR SIMILAR ARTICLES.

SPECIFICATION forming part of Design No. 35,360, dated December 3, 1901.

Application filed October 12, 1901. Serial No. 78,512. Term of patent 7 years.

To all whom it may concern:

Be it known that I, WILLIAM H. ROGERS, a citizen of the United States, residing at Plainfield, Union county, State of New Jersey, have invented and produced a new and original Design for a Handle for Spoons, Forks, or Similar Articles, of which the following is a specification.

My invention relates to a design for a spoon and similar tableware; and it consists of a handle which is rounded at the top and that tapers toward the bowl and with certain configuration of said handle and novel ornamentation upon said handle, as shown in the accompanying drawing.

My design consists in a twisted rope-like molding that surrounds the edge of the handle and follows the configuration of the handle and has two coil-like turns in the twisted rope-like molding at the top of the handle.

A represents the bowl of a spoon, and B the handle thereof, and C represents the two coil-like turns in the twisted rope-like molding. The configuration of the handle B is tapering from the top point to *a* and again enlarging to a point at *b* and thereafter again tapering to the point *c*, where there is an enlargement at the juncture of the handle with the bowl. Within the edge molding there is a line upon the otherwise smooth surface of the handle, which line is ornamental in its design.

What I claim is—

The design for a handle for spoons and similar articles, as herein shown and described.

WILLIAM H. ROGERS.
